HOSIERY WITH EXTERNAL WELTS INCORPORATING ELASTIC YARN

Joseph D. Rambo, Norristown, Pa., assignor to
 Rambo & Regar, Inc., Norristown, Pa., a corporation of Pennsylvania

Application April 29, 1938, Serial No. 205,094

4 Claims. (Cl. 66—173)

This invention relates to knit hosiery and it has for its object to provide one or more knit covered rubber elastic garter courses in the leg, incorporated in narrow circumferential tubular 5 welts lying entirely on the external surface of the stocking, the purpose of the invention being to enhance the comfort of the stocking in that the covered rubber elastic does not form part of the inner surface of the knitting which makes 10 contact with the leg, so that it does not press into the skin, and the unbroken inner surface of the knitting acts as a cushion to hold the elastic courses away from the skin.

Other objects of the invention will appear as 15 the following description of a preferred and practical embodiment of the same proceeds.

In the drawing throughout the several figures of which the same characters of reference have been employed to designate identical parts:

20 Figure 1 is a view in elevation of the upper part of a knit stocking embodying the features of the present invention;

Figure 2 is a section showing several of the 25 external welts embodying the elastic courses;

Figures 3, 4 and 5 show successive steps by 30 which the stocking of the present invention may be made on a circular non-rib dial machine; and

Figures 6, 7 and 8 are a series of views showing successive steps in the making of the stocking 35 of the present invention on a flat rib machine.

Referring now in detail to the several figures the numeral 1 represents the upper leg portion of a stocking which may be plain knit on a circular dial machine of the type indicated in 40 Figures 3, 4 and 5 or rib knit on a flat machine of the type suggested in Figures 6, 7 and 8.

The stocking as shown is formed with one or 45 more external narrow tubular welts 2 which begin and end at the same point, so that no part of the welt appears on the inner surface 3 of the stocking. The change of thread from the basic fabric of the stocking to the covered elastic rubber thread 4 takes place in the welt, the elastic courses being solely in the welt, the change 50 from the covered rubber yarn to the basic yarn being effected before the completion of the welt.

According to the present invention there may be one or a larger number of the external welts carrying the covered rubber elastic courses and 55 these may be placed at any desired position in the leg portion of the stocking.

Referring to Figures 3, 4 and 5, in which the dial bits are represented by the reference characters 5 and the cylinder needles by 6, it will be 55 assumed that the welt is to be knit at a distance

from the top of the stocking. The portion 7 of the knitting represents the free part of the top of the stocking above the welt. This is made of the basic relatively inelastic yarn. Figure 4 shows that the bit 5 has withdrawn a course of loops 5 from the cylinder needles 6 and that the portion of the knitting 8 between the bits and needles is being incorporated in the welt. The change from the basic yarn to the covered elastic rubber yarn takes place in this portion of the knitting, the 10 elastic yarn being shown dark and indicated by the reference character 9. Figure 6 shows that the bits 5 have returned the withdrawn loops to the needles 6 completing the welt 2 and that the needles have knit a further portion 10 of the leg 15 of the stocking below the welt. The change of thread from covered rubber elastic to the basic yarn of the stocking was made before the completion of the welt as is clearly shown in Figure 5.

Figures 6, 7 and 8 show the making of the 20 same type of welt in a flat rib machine in which the needles 11 pull the loops in one direction while the needles 12 pull it in the opposite direction forming the ribs. In Figure 6 the portion of 25 the knitting 13 indicates the free part of the stocking leg above the welt. In Figure 7 the needles 11 are stationary merely holding the knitted portion 13 while the needles 12 are knitting the part 14 which will be incorporated into the welt. The thread from the knitting is of 30 course supplied by a carrier or carriers, not shown. The covered rubber elastic yarn is incorporated in the part 14.

Figure 8 shows that the welt 2 has been completed by the needles 11 resuming the knitting, 35 the needles alternately drawing the loops in opposite directions forming the portion 15 of the stocking leg which lies below the welt. As in that form of the invention described in connection with Figures 3, 4 and 5, the incorporation of the 40 covered rubber elastic thread in the welt terminates before the welt is completed.

In both forms of the invention, referring to Figures 5 and 8, it will be obvious that the welt lies altogether externally of the main web of the 45 knitting so that the welt does not come into contact with the leg, but is cushioned by the interposition of the main web of the knitting between the welt and the leg. This as stated enhances the comfort of the stocking by preventing the 50 covered rubber elastic courses coming directly into contact with the leg and embedding themselves into the skin. The narrow welts also constitute a feature of adornment in the stocking.

While I have in the above description disclosed 55

several illustrative methods by which the stocking of the present invention can be made, it will be understood to those skilled in the art that these do not exhaust the several ways in which such a welt can be constructed and all of which are to be considered within the scope of the present invention as defined in the appended claims.

What I claim is:

1. Knit hosiery including a leg portion and a plurality of integrally knit spaced narrow tubular welts formed externally of said leg portion, and having elastic rubber yarn knit into the tubular structure of said welts, said leg portion behind said welts constituting a cushion between the leg and said welts.

10 2. Knit hosiery including a leg portion and a plurality of integrally knit spaced narrow tubular welts formed externally of said leg portion, said welts including garter courses of covered elastic

rubber yarn, said leg portion constituting a cushion between the leg and said welt.

3. Rib knit hosiery including a leg portion and a plurality of integrally knit spaced narrow tubular welts formed externally of said leg portion, 5 said welts beginning and ending at the same course, said welts including garter courses of covered rubber elastic yarn, that part of said leg portion behind said welts forming a cushion between the leg and said welts.

10 4. In a knitted stocking, a single ply top formed principally of inelastic yarn and having knitted integrally therewith and projecting outwardly therefrom a plurality of vertically spaced circumferential tubular welts knitted of elastic yarn, 15 each welt beginning and ending at one and the same course of said top.

JOSEPH D. RAMBO.
